UNITED STATES PATENT OFFICE.

THEODORE F. GENSMER, OF MINNEAPOLIS, MINNESOTA.

SHOE-SHINING DEVICE.

1,218,393.

Specification of Letters Patent.

Patented Mar. 6, 1917.

Application filed February 21, 1916. Serial No. 79,581.

To all whom it may concern:

Be it known that I, THEODORE F. GENSMER, citizen of the United States, resident of Minneapolis, county of Hennepin, State of Minnesota, have invented certain new and useful Improvements in Shoe-Shining Devices, of which the following is a specification.

My invention relates to a shoe shining device similar to the one illustrated and described in my pending application for U. S. Patent, No. 27,448, filed May 11, 1915.

The object of my invention is to provide a shoe shining device having a dauber head which can be easily and quickly removed from the supporting handle and a new head substituted, thereby avoiding the necessity of throwing away the entire device when the bristles of the dauber are worn out.

20 A further object is to provide a dauber in which the paste will be uniformly distributed to the bristles.

25 A further object is to provide a magazine or paste container which can be sold separately from the brush and be inserted easily and conveniently into the brush handle preparatory to the operation of feeding the paste to the brush bristles.

30 Other objects of the invention will appear from the following detailed description.

The invention consists generally in various constructions and combinations, all as hereinafter described and particularly 35 pointed out in the claims.

In the accompanying drawings forming part of this specification.

Figure 1 is a longitudinal sectional view through a shoe shining device embodying 40 my invention,

Fig. 2 is a top view, partially in section, of the same,

Fig. 3 is a transverse sectional view on the line $\alpha-\alpha$ of Fig. 1,

45 Fig. 4 is a view of the paste container that is inserted into the hollow handle,

Fig. 5 is a detail view of a modified construction,

50 Fig. 6 illustrates a form of cap for the magazine shown in Fig. 5,

Fig. 7 is a side view, partially in section, showing the paste-applying brush mounted in the finishing brush,

Fig. 8 is a top view of the same,

Figs. 9 and 10 are detail views of a modified means for fastening the cover on the hollow paste-containing handle,

Fig. 11 is a detail sectional view, showing a modified construction of the hollow handle and the parts fitting therein,

60 Fig. 12 is a similar view, showing a paper magazine or container and the washer having the point for cutting the walls of the paper magazine.

In the drawing, 2 represents the head of 65 the dauber brush, made of suitable material, preferably wood, having comparatively long bristles 3 in one end and similar but shorter shoe cleaning bristles 4 in the opposite end. A central orifice 5 is provided in the head 70 and a tube 6 is inserted into said orifice and has a threaded end to receive the screw 7 which locks the tube therein. A port 8 is provided in the wall of said tube, communicating with a similar tube 9 which extends 75 centrally in the head 2 and into the bristles 3.

The dauber head is preferably made in the form shown, so that by removing the 80 screw 7 the head may be detached from the handle and a new one substituted when the bristles of the dauber become worn, or clogged with paste. The tube extending down into the bristles serves to conduct the paste to the extremities of the bristles and 85 deliver it uniformly thereto.

A cylinder 10 is seated at one end against the head 2 and forms the handle of the brush. A ring 11 is fitted snugly into the open end of the cylinder and has a central 90 opening 12 therein to receive the projecting end of the tube 6. A paste magazine or container 13 is adapted to fit into the cylinder 10. This magazine is illustrated in detail in Fig. 4 and comprises the cylindrical body portion and covers 14 and 15 for the ends thereof, one end being preferably provided with an annular rib 16 projecting sufficiently to prevent that end from being inserted into the cylinder.

100 The paste magazine is adapted to contain any suitable form of paste for polishing shoes or the surfaces of other articles, and through the application of the follower therein will be constantly under pressure, thereby preventing the air from entering the magazine and drying the paste.

A cap 17 is threaded to engage the threads

in the end of the cylinder and encircles the projecting end of the paste magazine. This cap is provided with a hub 18 having a handle 19 shrunk thereon to revolve the hub when the handle is turned. The hub has a left-hand thread to receive a feed screw 20 provided with a rib 21 at its outer end which prevents the screw and the hub from separating. The other end of the screw is adapted to stick into the magazine of paste when the cover 15 is removed therefrom and is provided with a follower 22 of suitable material, and a washer 23 that is threaded on said screw and has a limited movement thereon between the stops 24 and 25. When the handle 19 is revolved with the hub 18, the screw will be fed inwardly until the rib 21 contacts with the hub and during this movement the follower 22 will be advanced with the screw to feed the paste. When the screw reaches the limit of its longitudinal movement, the continued revolution of the hub and handle will revolve the screw also and thereupon the follower 22 and the washer 23 will continue to advance and eject the paste from the magazine. The feed screw may be adapted for any desired length of stroke in the cylinder.

The washer 23 has a lug 26 thereon to contact with a longitudinal rib 27 in the magazine. This rib will prevent the washer from turning with the screw and will feed it inwardly toward the brush-head.

Fig. 2 illustrates the position of the parts when the paste magazine has been inserted into the hollow handle and the cap is about to be replaced and the feeding operation begun. The revolution of the screw when its forward movement has been checked, as above described, will cause the washer 23 that is threaded on the screw to be fed forward thereon to advance the follower and continue the feed of the paste until the follower reaches the inner end of the screw and contacts with the stop 25, at which point the follower may be discarded and left in the magazine, thereby preventing the formation of a vacuum when the screw is withdrawn from the magazine. A new follower will be furnished with each tube or magazine of polish.

In Fig. 5 the outer end of the magazine is shown, provided with a series of teeth. These teeth are adapted to engage a surface 29 in the cap for the purpose of revolving the magazine in the hollow handle and seating its inner end firmly against the head of the cylinder forming the handle.

In Fig. 7 I have shown a finishing brush 30 having a socket 31 therein to receive the head 2 and preferably provided with a clip 32 in position to be engaged by a pin 33 for locking the brush and paste-applying device together temporarily. This head 2 may also be made to fit snugly in the

socket 31 and be held therein by its frictional engagement with the walls of the socket.

In Figs. 9 and 10 I have shown a modified means for fastening the cap 17 on the end of the cylinder, which consists in providing bosses 34 in the walls of the cylinder to enter grooves 35 formed in the walls of the cap, said grooves having offsets at their ends extending through the edge of the cap to allow the entrance of the bosses therein.

In Figs. 10 and 11 I have shown a modified construction of cylinder, which consists in seaming the edges at 36, the magazine fitting therein being also seamed in a similar manner, these seams projecting inwardly and forming a stop to hold the washer against revolution.

In Fig. 12 a magazine 37 is provided, consisting preferably of paper having a longitudinal depression 38 at the point where the cylinder is seamed to receive the said seam and the washer 39 has a sharpened point or spur 40 which digs into the paper and holds the washer against revolution and also cuts through the wall of the paper, preventing the use of the magazine a second time.

This shining device, while shown and described for use in shining shoes, may be used for polishing stoves or other surfaces.

I claim as my invention:

1. A shoe shining device comprising a hollow handle adapted to contain a suitable paste, a tube forming a longitudinal continuation of said handle and through which the paste is fed, a dauber head having a socket extending therethrough to receive said tube, means mounted in the end of said tube and engaging said dauber head for holding it in place thereon, said head having bristles and said tube being provided with a branch extending into said bristles for delivering paste thereto.

2. A shining device comprising a handle adapted to contain a shining paste, a tube communicating with the interior of said handle and forming a longitudinal continuation thereof, a dauber head having a socket to receive said tube and fitting snugly against the end of said handle, a screw engaging said dauber head and tapped into said tube for locking said head and tube together, the removal of said screw allowing the separation of said head from said handle, bristles mounted in said head, and said tube having a discharge port therein leading to said bristles.

3. A shining device comprising a hollow handle having a dauber brush and a feed passage communicating with said handle, a paste magazine fitting within said handle, a feed screw for said paste magazine, a follower for said feed screw, means feeding

said screw lengthwise initially to advance said follower and for revolving said screw and moving said follower on said screw when lengthwise movement of the screw 5 has ceased.

4. A shining device comprising a hollow handle, a brush having bristles and a feed passage leading from said bristles to said handle, a removable cap for said handle, a 10 paste magazine fitting within said handle, a feed screw mounted within said cap and a hand grip for feeding said screw lengthwise a predetermined distance, a follower mounted on said screw and having means 15 for advancing it into the paste through the revolution of said screw when its forward movement has ceased.

5. A shining device comprising a hollow

handle, a dauber head having bristles and a feed passage communicating with said 20 hollow handle, a cap for said hollow handle, a hub mounted thereon and a handle for said hub, a feed screw passing through said hub and having a limited longitudinal movement therein when said hub and handle are revolved, a follower mounted on said 25 screw and advanced into said hollow handle by the longitudinal movement of said screw, the revolution of said hub and handle revolving said screw when its longitudinal 30 movement has ceased and continuing the feeding movement of said follower in said handle.

In witness whereof, I have hereunto set my hand this 16th day of February, 1916. 35

THEODORE F. GENSMER.
